UNITED STATES PATENT OFFICE.

NICK SCHLEICH AND CLARENCE J. ALDRIDGE, OF GREAT FALLS, MONTANA, AS
SIGNORS OF ONE-THIRD TO JACOB J. GOERGEN, OF GREAT FALLS, MONTANA.

ELECTRIC CIRCUIT CLOSER.

Application filed December 27, 1926. Serial No. 157,255.

The primary object of the invention is the provision of means for automatically closing the circuit of adjacent cars when coupled, and breaking said circuit when the cars are uncoupled and interrupting the connection between the circuit closer and the electric conductor. Obviously, the invention is susceptible of general application in connection with movable parts for automatically connecting electric conductors when said parts are brought together and breaking the circuit when said parts are separated.

The invention provides an arrangement which is certain and positive in action, automatic in operation and simple in construction, embodying a few number of parts which are adapted to be readily and conveniently assembled and easily accessible for repairs or other desired purposes.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof reference is to be had to the following description and the drawing hereto attached, in which,—

Figure 1 is a central, longitudinal sectional view of an electric circuit closer embodying the invention, showing the relation of the parts when in neutral position;

Figure 2 is a similar view showing the relation of the parts when the circuit is closed.

Corresponding and like parts are referred to in the following description and designated in both views of the drawings by like reference characters.

The numerals 1 and 2 designate movable parts, such as members of a car coupling, which are adapted to be brought together and close the circuit represented by the elements 3 and 4 which are conductors through which the electric circuit is closed when the parts 1 and 2 are brought together, as indicated most clearly in Figure 2. The part 1 is provided with a metal socket 5 which is electrically insulated therefrom, and to which the conductor 3 is electrically connected. The part 2 is likewise provided with a metal socket 6 which is electrically insulated therefrom, and to which the conductor 4 is electrically con-

nected. The openings of the sockets taper slightly to insure a positive connection when the circuit is closed, as indicated most clearly in Figure 2. A chamber 7 is formed in the part 1 and a ring 8 is threaded into the outer end thereof, and serves to retain the circuit closer within the chamber 7.

The circuit closer is slidably mounted within the chamber 7 and comprises sections or members 9 and 10 which have an independent movement. The member 9 has a tapering extension 11 to enter the socket 5 and the member 10 is formed with a tapering extension 12 to enter the socket 6. A sleeve 13 is mounted upon the member 9 and is electrically insulated therefrom and connected thereto in any determinate way for movement therewith. The sleeve 13 is formed with an annular enlargement 14 to which a shell 15 is connected at its inner end, said shell having an inwardly disposed flange 15^a at its forward end. The annular enlargement 14 provides an abutment for two helical springs 16 and 17 which are disposed upon opposite sides of the sleeve 13. The spring 16 is arranged between the inner end of the chamber 7 and the enlargement 14, and normally urges the member 9 forwardly to hold its tapered end 11 clear of the socket 5, as indicated most clearly in Figure 1. When the member 9 is pressed rearwardly, the spring 16 is compressed.

The member 10 is formed with an axial opening 18 to receive a stem 19 projecting from the member 9. A sleeve 20, similar to the sleeve 13, is secured upon the member 10 and has an annular enlargement 21 forming a stop to limit the forward movement of the member and an abutment for the forward end of the spring 17. The sleeve 20 is electrically insulated from the member 10 and may be connected thereto in any determinate way. The forward end of the stem 19 is fixed and spread to insure a positive connection with the walls of the opening 18.

When the circuit closer is in neutral position the parts are arranged substantially as shown in Figure 1, the enlargement 21 being in contact with the inner flange 15^a of the shell 15, and said flange 15^a being in contact with the confining ring 8, as indicated most clearly in Figure 1. When the parts 1 and 2 are brought together, the circuit closer is moved rearwardly and the tapered ends 11 and 12 enter the respective sockets 5 and 6, thereby completing the cir-

cuit through the electric conductors 3 and 4, as indicated most clearly in Figure 2. When the parts 1 and 2 are separated, as indicated in Figure 1, the spring 16 moves the member 9 forwardly to break connection thereof with the socket 5, and the spring 17 moves the member 10 forwardly to bring the elements 15^a, 21 and 8 into contact.

Having thus described the invention, we claim:

1. In combination with a part having a chamber formed therein, a socket at the inner end of the chamber, a confining ring at the outer end of said chamber and a circuit closer within the chamber and held in place by said confining ring, and comprising two members having a telescopic connection, a helical spring interposed between the two members to normally urge them apart and a helical spring between the inner end of the chamber and the inner member and normally urging the circuit closer as a whole towards the outer end of the chamber.

2. In combination with a part having a chamber, a socket at the inner end of the chamber, a confining ring at the outer end of the chamber, a member having an outer enlargement and extending through the said confining ring and limited in its forward movement by the enlargement thereof and the said confining ring, a companion member within the inner portion of the chamber, and having a telescopic connection with the first mentioned member and formed with an annular enlargement, a helical spring interposed between the two members, a second helical spring interposed between the inner end of the chamber and the inner member, and a shell secured to the enlargement of the inner member and having an inner flange at its forward end to engage the said confining ring and the annular enlargement of the forward member.

3. The combination with movable parts, one of the parts having a chamber formed therein, a socket at the inner end of the chamber, a second socket carried by the cooperating part, members loosely mounted within the said chamber, each having an annular enlargement and a tapered projection to coact with the respective sockets, one of the members having an axial opening and the

other member provided with a stem telescoping the said opening, a helical spring interposed between the two members, a second helical spring arranged between the inner end of said chamber and the inner member, and a shell secured to the annular enlargement of the inner member and loosely receiving the annular enlargement of the outer member and provided with an inner flange adapted to come between the said confining ring and the annular enlargement of the outer member.

4. An electric circuit closer including a fixed contact, an end sliding member, an intermediate sliding member telescoping the end member and provided with a contact to close the circuit through the fixed contact, an open helical spring normally holding the two members pressed apart, and a second open helical spring normally holding the intermediate member away from the fixed contact.

5. An electric circuit closer including a fixed contact, an end sliding member having an axial opening, an intermediate sliding member having a stem slidable in the axial opening of the end member and provided with a contact to close the circuit through the fixed contact, an open helical spring normally holding the two members pressed apart, and a second open helical spring normally holding the intermediate member away from the fixed contact.

6. An electric circuit closer including a fixed contact, an end sliding member, an intermediate sliding member telescoping the end member and provided with a contact to close the circuit through the fixed contact, an open helical spring normally holding the two members pressed apart, a shell enclosing the spring and attached at one end to one of the members and having its opposite end slidably engaging the other member and normally limiting the separation of the two members, and a second open helical spring normally holding the intermediate member away from the fixed contact.

In testimony whereof we affix our signatures.

NICK SCHLEICH. [L. S.]
CLARENCE J. ALDRIDGE. [L. S.]
